Milwaukee, Wis., a corporation of Delaware

Application January 5, 1933, Serial No. 650,256

14 Claims. (Cl. 183—58)

This invention relates in general to a dust collector of the type wherein fabric bags are used to separate suspended solids from gases, and more particularly to improved apparatus for alternately slackening and tensioning the various bags of a dust collector in a predetermined periodically recurring sequence.

In the dust collecting art it has heretofore been proposed to shake the bags of a dust collector by means of various mechanical mechanisms, for example, by means of a continuously rotating shaft having a plurality of bag shaking cams thereon and mechanical mechanism for periodically moving a bag shaking member into and out of the path of travel of said cams. In such systems it is extremely difficult and hazardous to make repairs or adjustments on the various bag shaking units because of the continually rotating cams which cannot be stopped without shutting down the whole installation. Moreover, in such systems it is impossible to readily determine whether or not all of the units are properly completing their cycle of operations. In bag shakers of the prior art trouble has also been experienced with the mechanism which connects the bags and the cams; often resulting in breakage due to the large impact forces occurring when the bags are suddenly snapped upwardly.

It is an object of the present invention to obviate the above difficulties by providing a dust collector system in which the various dust collecting units are individually operated by cam shafts driven by electric motors which are automatically started in a predetermined sequence by means of switch mechanism and each stopped after a predetermined number of revolutions so that the bags always remain in their slackened position during the time the motors are at rest.

Another object of the invention is to provide a system of the above character in which manually operable switches located near each motor are provided for stopping the operation of said motor so that repairs and adjustments can be made without stopping the whole system.

Another object of the invention is to provide a system of the above character in which manually operable switches are provided for starting and stopping any one of the bag shaking units independent of the automatic mechanism.

A further object of the invention is to provide a dust collector system in which a motor driving a cam-actuated bag shaking unit is periodically started, and thereafter maintained running for a predetermined number of alternate bag

slackening and tensioning operations by means of a limit switch which may be adjusted so that the motor driven cam stops at variable positions so as to thereby adjustably predetermine the amount of slack maintained in the bags while the motor is idle.

A still further object of the invention is to provide a bag shaking system in which the shock of the sudden tensioning of the bags is cushioned by means of a spring which is interposed between each bag supporting member and the mechanism which is operatively biased into engagement with the motor driven cam.

These and other objects and advantages are attained by this invention, various novel features of which will be apparent from the description and drawings herein, and will be more particularly pointed out in the claims.

Various illustrative examples of the application of this invention are shown in the accompanying drawings in which:

Fig. 1 is a side view of an improved bag shaking mechanism embodying features of the invention.

Fig. 2 is a top view of Fig. 1.

Fig. 3 is a schematic diagram of a dust collecting system embodying features of the invention.

Referring more particularly to Figs. 1 and 2, the bag shaking mechanism comprises a bed plate 10 having a lever 11 which is provided with a fulcrum pin 12 journaled in bearings 13 which are mounted on the bed plate 10. The right hand end of lever 11 is provided with a hole having a spherical bearing surface adapted to engage a spherical enlargement on sleeve member 14 which projects through said hole. A connecting rod 15 is threaded through sleeve member 14 and is adjustably locked thereto by means of nut 16. The lower part of connecting rod 15 slidably extends through guide sleeve 17 which is attached to bag supporting frame 18. A cushioning spring 19 is interposed between the sleeve member 17 and nut 21 which is attached to connecting rod 15. A plurality of dust collecting bags 22 are symmetrically attached to frame member 18 by means of bag head members 23 and bolt members 24. Lever member 11 is also provided with a trunnion 25 upon which a saddle block 26 is downwardly biased by means of springs 27 and 28, noting that guide block 29, located between the upper and lower sections of the springs, is provided to prevent buckling of these springs. A spring cap 31 is adjustably held in place by means of lock nuts 32 on tension rod 55

33 which is connected at its lower end to base member 10. A pair of safety rods 34 extends from saddle block 26 slidably through lugs on spring cap 31 and serves to prevent springs 27 and 28 from flying upward and also serves to hold springs 27 and 28 in compression when such springs are being replaced. The left hand end of lever 11 is provided with a renewable wear plate 35 adapted to be pressed into engagement with cam 36 by means of the above described springs. Cam 36 is keyed or otherwise secured to cam shaft 37 which is journaled in bearings 38 carried by base member 10.

Referring now to Fig. 3, the dust collector system comprises a plurality of separate dust collector units 39, 40 and 41. Each of these units is in communication with a source of dust laden air of which conduit 42 is a part. Dust laden air is carried from conduit 42, when valve 43 is open, through header 44 and upwardly through the various dust collecting bags 22. The gas filters through the fabric of bags 22 leaving the solid particles behind, which are periodically precipitated into collecting hoppers 45.

25 Cam shaft 37 is driven at a low speed by electric motor 46 through speed reducer 47, which is preferably of the gear type. An electromagnetically releasable friction brake 48 has its solenoid 49 connected across the terminals of motor 46. 30 The electric motor of each unit is connectible to conductors 51, 52 and 53 of a power line by means of line switch 54 when the operating coil 55 thereof is energized from the control bus 56, 57 which is in turn connected to conductors 51 and 35 52 or any other suitable source of power.

Apparatus 58 for periodically initiating the starting of the respective motors comprises a drum controller 59 adapted to be continuously rotated by means of an electric motor 61 which is connected thereto by means of gearing 62, or any suitable ratcheting device. Motor 61 is normally connected to power line 63 through switch 64 and fuses 65, noting that this power line may be energized from the same source as power line 45 having conductors 51, 52 and 53, or from a different power source. A conductor 66 is normally connected to conductor 51 by means of no-voltage relay 67. A plurality of contacts including 68, 69, 70 are arranged to be periodically and sequentially bridged by means of a plurality of spaced segments including 71, 72 and 73, which are preferably of the quick acting type in order that circuits may be broken thereby in event of the failure of a limit switch as will be more particularly described hereinafter. Control lines 74, 55 75 and 76 are connected with contacts 68, 69 and 70 respectively.

Each unit is provided with a start push button 71 and a stop push button 78 located in the vicinity of the motors respectively. Start push button 79 and stop push button 80 are located at a remote central control panel. Each motor is provided with a thermo overload switch 81 adapted to open a control circuit upon occurrence of overload in the motor associated therewith. A relay, having its operating coil 82 connected in parallel with operating coil 55, is provided with normally open contacts 83; and a relay, having an operating coil 84 connected across control bus 56, 57 through overload switch 81, is provided with contact 85 which is held open as long as switch 81 is closed and potential exists on the control bus. A transformer 86, energized from conductors 52 and 53, is arranged to supply current to signal lamp 87 when contacts 83 are

bridged and to signal lamp 88 and annunciator 89 when contacts 85 are bridged. Line switch 54 is provided with an auxiliary contact 90 which is adapted to close when coil 55 is energized. A limit switch schematically shown by reference numeral 91 is arranged to be actuated by a cam 92 which is driven from cam shaft 37 by means of gearing 93. Valve 43 is normally held open by means of a spring 94 and is operable to its closed position by means of a solenoid 95 which is connected across the terminals of motor 46.

The automatic operation of the above described apparatus is as follows. All of the switches and apparatus are shown in the positions corresponding to complete shut-down of the dust collector system, noting that dust laden gas will continue to flow to the various units unless the blowers (not shown) associated with the source of dust laden gas are also stopped. In order to start the system, it is necessary to close switch 64, thus starting motor 61 and also closing relay 67. With drum controller 59 in the position shown, closure of relay 67 will establish a starting circuit for the motor associated with unit 39 from conductor 51 through the contacts of relay 67, contacts 68 and 71, conductor 74, through stop push buttons 80 and 78 associated with unit 39, through both operating coils 55 and 82 in parallel, through overload switch 81 to control bus 57 which is connected to line conductor 52. Energization of operating coil 55 causes line switch 54 to close, thereby causing motor 46 associated with unit 39 to start rotating in a clockwise direction. After a predetermined number of revolutions of motor 46 cam 92 will close limit switch 91 which thereupon establishes a maintaining circuit for operating coil 55 which may be traced from control bus 56 through switch 91, through auxiliary contact 90, through stop buttons 80 and 78, through operating coil 55, and through overload switch 81 to control bus 57. It is thus to be noted that the continued rotation of drum controller 59 so that contact 71 breaks engagement with contacts 68 will not stop the motor 46 inasmuch as the above described maintaining circuit is independent of the aforescribed starting circuit.

Simultaneous with the energization of motor 46 solenoid 49 will release brake 48 and solenoid 95 will operate to stop the flow of dust laden gas from conduit 42 to header 44.

The energization of the relay having operating coil 82 simultaneously with the energization of operating coil 55 will close contacts 83, thereby lighting lamp 87 to give a visual indication that motor 46 of unit 39 is in operation. After cam shaft 37 has rotated through a portion of a revolution the shoulders of cams 36 will move out of engagement with the corresponding wear-plates 35, thus permitting springs 27 and 28 to suddenly rotate levers 11 in a counter-clockwise direction, thereby snapping bags 22 in an upward direction. Due to inertia the bag supporting frame 18 will move a greater distance than the actual travel of the right hand end of lever 11 and upon return of the frame 18 the shock of the rebound will be absorbed by cushioning spring 19 which will thereupon act to impart a secondary shaking motion to the suspended bags 22.

After a predetermined number of bag shaking operations, as above described cam 92 will have 70 rotated into such a position that switch 91 will snap open, thereby breaking the maintaining circuit for line switch 54. The deenergization of motor 46 will immediately cause the application of brake 48 and the opening of valve 43 by means 75

of spring 94. The opening of valve 43 again starts the dust filtering phase of the operation of the system. Cam 92 is of such a shape that limit switch 91 will be opened in timed relation with respect to the position of cams 36 so that when the motor 46 comes to rest, the lobes of cams 36 will hold the bags 22 in their slackened position. It has been found that the bags in their slackened position often lengthen and form loops which 10 constrict the flow of dust laden gas therethrough, and to obviate this difficulty, limit switch 91 is constructed so that it may be caused to open in adjustable timed relation with respect to the position of cams 36 so that the motor may be stopped 15 in such a position that the cams 36 will not have actuated the bags 22 to their completely slackened position. For example, the amount of slack in the bags can be adjusted by adjusting the angular position of cam 92 with respect to the cam 20 shaft 37.

The continued rotation of drum controller 59 causes segment 72 to bridge contacts 69, thereby establishing a starting circuit for the motor associated with unit 40 through conductor 75. The 25 energization of conductor 75 from line conductor 51 through relay 67 and contacts 69 and 72 through operating coil 55 of the line switch 54 associated with motor 46 of unit 40 initiates a cycle of operations which is exactly the same as 30 that above described, and need not, therefore, be further described. It is to be noted, however, that contact segment 72 on drum controller 59 may be so spaced with respect to contact segment 71 that the second unit will be started either 35 slightly before or slightly after the first unit has completed its cycle of operations.

A further rotation of drum controller 59 will cause contact segment 73 to bridge contacts 70, thereby establishing a starting circuit through 40 conductor 76 and operating coil 55 of the line switch 54 associated with unit 41 and so on for the other units of the system which, for the sake of simplicity, have not been shown. It is to be understood that a complete dust collector system 45 will usually comprise more units than herein illustrated and that the various units will be arranged throughout the structure which houses the system in such a manner that there will be a plurality of units in various parts of the structure 50 operating at all times and in overlapping sequence.

If an overload should occur in any one of the above described motors thermal overload switch 81 will open, thereby stopping the corresponding 55 motor and preventing the re-starting of the same until the trouble has been ascertained. The opening of overload switch 81 deenergizes operating coil 84, thereby causing contacts 85 to close, which thereupon close the circuit to signal lamp 88 and annunciation 89 which immediately warn the operator that a motor has stopped for some abnormal reason.

Any one of the above described units may be 60 manually started and stopped in a number of different ways. For example, if it is desired to make repairs or adjustments on any unit push button 78 located in the vicinity of that unit may be opened and in this position it is impossible for the drum controller to start the motor and it is 65 also impossible for an operator at the switch board panel to start that particular motor by means of push button 79. However, it is possible for the repair man to inch the bag shaker mechanism to any desired position by means of push button 77 provided stop button 78 or 80 is

opened, noting that if stop buttons 78 and 80 are both closed it is possible to initiate the starting of the motor associated therewith by means of either push button 77 or 79, in which event the stopping will be under the control of limit switch 91 in the usual fashion. It is thus seen that it is possible to manually control the starting and stopping of any one of the units either from a remote control point or from a point adjacent the motor by means of manually controlled push 10 buttons independent of the automatic operation normally initiated by the continually rotating drum controller 59.

If it is desired to completely shut down the system, switch 64 will be opened which causes 15 relay 67 to drop, noting, however, that any unit then in operation will continue its cycle of operations and come to rest with the bags in their slackened position. If it were not for relay 67 the stopping of drum controller 59 on an active contact position would cause one or more of the units to continue their shaking operation indefinitely.

It is to be understood that the invention claimed herein is not limited to the exact details of construction herein illustrated, for obvious modifications will be apparent to persons skilled in the art without departing from the spirit and scope of the invention as defined in the appended claims.

It is claimed and desired to secure by Letters 30 Patent:

1. A dust collector comprising in combination, a source of dust laden gas, a dust collecting unit having at least one vertically disposed bag arranged to receive dust laden gas from said source, means for alternately slackening and tensioning said bag comprising an electric motor, a cam driven by said motor and also comprising mechanism for operatively connecting said cam with said bag, switch mechanism for periodically initiating the starting of said motor, and means driven in accordance with the rotation of said cam for keeping said motor running until said cam has completed a predetermined number of revolutions, said last means including mechanism for stopping said motor in such a position that said cam and said mechanism associated therewith maintain said bag in its slackened condition while said motor is at rest.

2. A dust collector comprising in combination, 50 a source of dust laden gas, a dust collecting unit having at least one vertically disposed bag arranged to receive dust laden gas from said source, means for alternately slackening and tensioning said bag comprising an electric motor, a cam 55 driven by said motor and bag suspending mechanism operable by said cam, switch mechanism for periodically initiating the starting of said motor, and switch means actuated by the rotation of said cam for keeping said motor running until 60 said cam has rotated a predetermined number of revolutions, said switch means including mechanism adjustable to cause said cam to stop at various positions relative to said bag suspending mechanism so as to thereby adjustably pre- 65 determine the slack in said bag during the time said motor is idle.

3. A dust collector comprising in combination, a source of dust laden gas, a dust collecting unit having at least one vertically disposed bag arranged to receive dust laden gas from said source, means for alternately slackening and tensioning said bag comprising an electric motor, a cam 70 driven by said motor and bag suspending mechanism operable by said cam, switch mechanism 75

- for periodically initiating the starting of said motor, and switch means actuated by the rotation of said cam for keeping said motor running until said cam has rotated a predetermined number of revolutions, said switch means including mechanism adjustable to stop said motor in timed relation to the position of said cam so as to thereby adjustably predetermine the amount of slack maintained in said bag while said motor is idle.
10. A dust collecting system comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for periodically shaking the bags thereof, said shaking means comprising an individual electric motor and a cam shaft driven thereby for each unit, a power line, a plurality of line switches each operable to connect and disconnect each of said motors to and from said power line, switch mechanism operable to automatically close said line switches sequentially and periodically, 15 said switch mechanism comprising a continually rotating controller operable to sequentially and periodically establish control circuits for said line switches, each unit having a control switch actuated upon the rotation of said motors respectively to maintain the respective control circuits established by said controller and to interrupt said control circuits respectively after said respective cam shafts have rotated a predetermined number of revolutions.
20. 5. A dust collecting system comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for periodically shaking the bags thereof, said shaking means comprising an individual electric motor and a cam shaft driven thereby for each unit, a power line, a plurality of line switches each 25 operable to connect and disconnect one of said motors to and from said power line, switch mechanism operable to automatically close said line switches sequentially and periodically, said switch mechanism comprising a continually rotating controller operable to sequentially and periodically establish control circuits for said line switches, each unit having a control switch actuated upon the rotation of said motors respectively to maintain the respective control circuits established by said controller and to interrupt 30 said control circuits respectively after said respective cam shafts have rotated a predetermined number of revolutions, and manually operable switches selectively operable to close and open any one of said line switches independent of the closure and opening thereof by said controller and said control switch.
25. 6. A dust collecting system comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for alternately slackening and suddenly tensioning the bags thereof, said means comprising an individual electric motor, a cam shaft driven thereby and also comprising a resilient connection between said cams and said bags, switch mechanism for periodically causing said motors to start and stop in a predetermined sequence, and means for closing the valves associated with the respective units while the motor associated therewith is running.
30. 7. A dust collecting system comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for alternately slackening and suddenly tensioning the bags thereof, said means comprising a plurality of cams and an electric motor drivingly connected with said cams and also comprising a plurality of springs for resiliently cushioning the sudden tensioning of said bags, and means for periodically starting and stopping said motors in a predetermined sequence.
35. 8. A dust collector comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for alternately slackening and suddenly tensioning the bags thereof, said means comprising an individual electric motor, a cam shaft driven thereby and also comprising a resilient connection between said cams and said bags, switch mechanism for periodically causing said motors to start and stop in a predetermined sequence, and means for closing the valves associated with the respective units while the motor associated therewith is running.
40. 9. A dust collector comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for alternately slackening and suddenly tensioning the bags thereof, said means comprising a plurality of cams and an electric motor drivingly connected with said cams and also comprising a plurality of springs for resiliently cushioning the sudden tensioning of said bags, and means for periodically starting and stopping said motors in a predetermined sequence.
45. 10. A dust collector comprising in combination,

for automatically closing said line switches sequentially and periodically comprising a continually operating master switch arranged to sequentially and periodically establish and interrupt control circuits for said line switches respectively, 5 means driven from said cam shaft for maintaining the respective control circuits established by said master switch and for interrupting said control circuits respectively after a predetermined number of revolutions of the respective cam shafts, and electromagnetic means responsive to the energization of said motors respectively for closing the valves associated therewith.

7. A dust collecting system comprising in combination, a source of dust laden gas, a plurality of 15 dust collecting units each having a plurality of vertically disposed bags arranged to receive dust laden gas from said source, a valve for each unit operable to stop the flow of dust laden gas to the unit associated therewith, each unit having means for periodically shaking the bags thereof, said shaking means comprising an individual electric motor and a cam shaft driven thereby for each unit, a power line, a plurality of line switches each 20 operable to connect and disconnect one of said motors to and from said power line, switch mechanism operable to automatically close said line switches sequentially and periodically, said switch mechanism comprising a continually rotating controller operable to sequentially and periodically establish control circuits for said line switches, each unit having a control switch actuated upon the rotation of said motors respectively to maintain the respective control circuits established by said controller and to interrupt 25 said control circuits respectively after said respective cam shafts have rotated a predetermined number of revolutions, and manually operable switches selectively operable to close and open any one of said line switches independent of the closure and opening thereof by said controller and said control switch.

8. A dust collector comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for alternately slackening and suddenly tensioning the bags thereof, said means comprising an individual electric motor, a cam shaft driven thereby and also comprising a resilient connection between said cams and said bags, switch mechanism for periodically causing said motors to start and stop in a predetermined sequence, and means for closing the valves associated with the respective units while the motor associated therewith is running.

9. A dust collector comprising in combination, a source of dust laden gas, a plurality of dust collecting units each having a plurality of vertically disposed bags arranged to receive dust laden gas from said source, a valve for each unit operable to stop the flow of dust laden gas to the unit associated therewith, each unit having means for alternately slackening and suddenly tensioning the bags thereof, said means comprising a plurality of cams and an electric motor drivingly connected with said cams and also comprising a plurality of springs for resiliently cushioning the sudden tensioning of said bags, and means for periodically starting and stopping said motors in a predetermined sequence.

10. A dust collector comprising in combination,

- a source of dust laden gas, a plurality of dust collecting units each having at least one bag supporting member with a plurality of vertically disposed bags attached thereto and arranged to receive dust laden gas from said source, each unit having at least one lever, means for resiliently connecting said bag supporting member to one end of said lever, a rotatable cam arranged to actuate the other end of said lever, spring means arranged to bias said other end of said lever into engagement with said cam, whereby said spring means is operable to periodically snap said bag supporting member upwardly during the rotation of said cam.
11. A dust collector, comprising in combination, a plurality of dust collecting units each having a plurality of vertically disposed bags arranged to receive dust laden gas, a lever associated with the bags of each unit and having one end resiliently connected thereto, means for so resiliently biasing each lever as to tension its associated bags, a rotatable cam associated with each lever and arranged to alternately move said lever against said biasing means to slacken said bags and release said biasing means to permit sudden tensioning of said bags, and means for periodically rotating each cam to actuate its associated lever.
12. A dust collector, comprising in combination, a dust collecting bag arranged to receive dust laden gas, a bag supporting member attached to said bag, resilient means disposed to support said bag supporting member, and a bag shaking device including a motor driven cam and a spring arranged to exert an impact upon said bag supporting member through said resilient means to snap said member upward to tension said bag, said resilient means functioning to prevent excessive

dynamic forces occurring in said bag shaking device when said bag is suddenly tensioned.

13. A dust collector, comprising a plurality of groups of dust collecting bags, means associated with each of said groups of bags for shaking the bags to clean them, an electric motor connected to each of said bag group shaking means to drive it, an electrical control system connected to said motors of said bag group shaking means and arranged to actuate them automatically in continually recurring sequence to clean each of said bag groups periodically, means associated with each of said motors for disconnecting it from said control system automatically upon the occurrence of abnormal conditions of operation, and means for indicating at a distance the functioning of said automatic disconnecting means preventing operation of its associated bag group shaking means in sequence.
14. A dust collector, comprising a plurality of groups of dust collecting bags, means associated with each of said groups of bags for shaking the bags to clean them, an electric motor operatively connected to each of said bag group shaking means, an electrical control system connected to said motors and arranged to initiate the operation of said motors automatically in continually recurring sequence, means actuated by each motor arranged to maintain said motor in operation until its associated bag shaking means has completed a predetermined cycle, and means for regulating said maintaining means to cause it to stop said bag shaking means with the bags in selected predetermined position.
